Inventor,

Walter M. Conger
by his attorney J. S. Johnson

UNITED STATES PATENT OFFICE.

WALTER M. CONGER, OF NEWARK, NEW JERSEY.

IMPROVEMENT IN CHILDREN'S TABLE-TRAYS.

Specification forming part of Letters Patent No. 123,332, dated February 6, 1872.

Specification describing certain improvements in Children's Table-Trays, invented by WALTER M. CONGER, of Newark, in the county of Essex and State of New Jersey.

Table-trays of sheet metal adapted to fit on the edge of the table, and turned down to overhang the edge and turned up at the other sides, have become a staple and important article of manufacture. One plan has been patented wherein the edges are turned up on all sides and legs soldered on to hang down over the edge of the table; but the legs are liable to become bent or broken.

I have, after much reflection and experiment, arrived at a form which can be manufactured with facility in one piece, and which has a front ridge as wide and smoothly rounded as may be desired, with a hanging lip at the front, extending down to the desired depth, formed in one piece therewith.

The accompanying drawing forms a part of this specification.

Figure 1 is a central vertical section, and Fig. 2 is a plan view of my improved tray complete. Figs. 3 and 4 represent one form of the spring-clips, which I prefer as fasteners. Fig. 3 is a view before being bent, and Fig. 4 a perspective view after being bent.

Similar letters of reference indicate like parts in all the figures.

The drawing represents what I consider the best means of carrying out the invention.

A is a sheet of metal, and I will designate by A¹, A², &c., the several portions which are turned upward and downward in the process of manufacture. The back is turned upward, as indicated by A¹. The two sides are turned upward, as indicated by A² A³. The front is turned upward to about half the height of the back and sides, as indicated by A⁴; it thence bends forward, presenting a broad and smoothly-rounded bead or broad ridge, which is a strong form of the metal, and well adapted to receive the pressure of the child's breast or naked arms; it thence extends downward, forming a deep vertical lip, and extends a considerable distance below the bottom A of the main body of the tray, as indicated by A⁵. The upper and lower edges are finished by folding the edges of the metal over upon a wire with ordinary tinner's tools or otherwise.

The finished tray is japanned, and may be decorated in any desired style.

I esteem it important, in practice, that the edge-wire B shall extend down from the upper to the lower edge, and guard the otherwise sharp edges of the metal where the transition occurs from the bent-up to the bent-down condition. It is so represented, and this feature may be introduced without further instructions to the tinsmith.

I esteem it also important that the cutting of the metal shall be so adapted to the dies that the bending up of the ascending front lip A⁴ shall just close with and join tightly to the bent-up side lips A² and A³. Solder may be applied along these lines to strengthen the union, if desired; but I believe the edging-wire B, extending along close to the edge, will sufficiently strengthen it.

My tray may be used with some success in the condition just described without the addition of spring-clips; but the addition, as shown, constitutes an important improvement.

Fig. 5 shows the spring-clips made from separate pieces of wire; these separate wires are stuck in close-fitting sockets, soldered on the outside of the lips A² A³, and allow of being turned out of the way when not in use.

I claim as my invention—

1. The within-described table-tray in one piece, having the front edge turned upward, as indicated by A⁴, and then downward, as indicated by A⁵, and adapted to serve as herein set forth.

2. In combination with the waiter or table-tray, constructed as above described, the edging-wire B, inclosed within the metal at the top of the lips A¹ A² A³, and at the bottom of the front hanging lip A⁵, and extending along close to the raw edges in the interval between, as and for the purposes specified.

3. The turning-clips C C, in combination with the table-tray, and adapted to retain the same against displacement in any direction, and to be turned around or folded out of the way when not in use, as herein specified.

In testimony whereof I have hereunto set my name in the presence of two subscribing witnesses.

WALTER M. CONGER.
